UNITED STATES PATENT OFFICE.

JOSEPH J. SLEEPER, OF MOORES, PENNSYLVANIA.

WRAPPER-PASTING DEVICE.

1,265,127.

Specification of Letters Patent.

Patented May 7, 1918.

Application filed April 29, 1916. Serial No. 94,299.

To all whom it may concern:

Be it known that I, JOSEPH J. SLEEPER, a citizen of the United States, residing at Moores, in the county of Delaware and State 5 of Pennsylvania, have invented certain new and useful Improvements in Wrapper-Pasting Devices, of which the following is a specification.

My invention relates to improvements in 10 wrapper pasting devices, the object of the invention being to provide improved means for controlling the outlet of paste so as to deposit the desired amount of paste on the wrappers.

15 A further object is to provide an improved construction of paste holder which can be readily dismantled, and taken apart, and effectually cleaned from time to time, as may be desired.

20 A further object is to provide an improved mounting for the paste holder which permits the latter to be tilted to any angle, and which insures a free vertical movement of the paste holder so that the latter feeds 25 downwardly as the wrappers are drawn out from under the same.

A further object is to provide a device of 30 the character stated which is an improvement upon the structure disclosed in Patent #1,033,282 granted to me July 23, 1912, and upon the structure disclosed in Patent 35 #1,084,825 granted to me January 20, 1914.

With these and other objects in view the invention consists in certain novel features 35 of construction and combinations and arrangements of parts as will be more fully hereinafter described and pointed out in the claims.

In the accompanying drawings:

40 Figure 1 is a top plan view, illustrating my improvements.

Fig. 2 is an elevation showing one side of the paste holder.

45 Fig. 3 is a view in section on an enlarged scale on the line 3—3 of Fig. 1.

Fig. 4 is an end view of the paste holder showing in dotted lines a tilted position, and

Fig. 5 is a plan view illustrating a modified shape of paste holder.

50 1 represents a base plate having two standards 2, 2, which are provided in their opposed faces with longitudinal grooves 3, to receive rollers 4 on my improved paste holder 5. The paste holder 5 is of general 55 trough shape and on its ends brackets 6 are

secured by bolts 7. The bolts 7 are projected through slots 8 in the brackets 6 and are secured by nuts 9 on the inside of the paste holder.

Each bracket 6 is provided with two slots 60 8 and two securing bolts 7, the latter of sufficiently less diameter than the width of the slots so that the paste holder can be adjusted at varying angles in either direction 65 as indicated clearly in dotted lines in Fig. 65 3, and this angular position of the paste holder affects a greater or less feed of paste as will be readily understood.

The brackets 6 are each provided with two rollers 4 which are disposed in vertical 70 alignment and move freely in the grooves 3. The rollers prevent any possibility of a binding action in the grooves, but insure a free vertical feed regardless of the angular disposition of the paste holder.

75 The paste holder 5 is provided with a bottom 9 having a series of perforations 10 therein, in line with perforations 12 in a removable false bottom 11. A sliding cut off plate 13 is located between bottom 9 and 80 false bottom 11 and is movable through a slot 14, in the wall of paste holder 5. This sliding plate 13 has an upturned flange 15 at its outer edge to facilitate its manipulation, and it will be readily understood by moving the plate 13 laterally relative to the 85 paste holder, the outlet of paste can be controlled or entirely cut off at the will of the operator.

The false bottom 11 fits snugly in the 90 paste holder and is provided with upwardly projecting tongues 16, slightly bent over at their upper edges as shown at 17 to facilitate the removal of the false bottom. The false bottom 11 and sliding plate 13 can both 95 be readily removed to allow a thorough cleaning of the device whenever occasion may require.

While I have illustrated in the drawing, the plate 13 consisting of two sections, 13^a 100 and 13^b of different lengths, I would have it understood that I do not limit myself to any number or length of plate sections, as I may vary the length of sections in order to accommodate any desired width of paste application.

105 The paste holder 5 is provided with perforated lugs 28 in which pins 18 are secured by screws 19. These pins 18 are positioned vertically and project below the bottom of 110

the paste holder so as to puncture the upper wrappers 20 and prevent accidental movement.

The wrappers 20 are disposed in a pile 5 on the base plate 1 and whenever desired, I provide a supporting block 21 preferably of glass under the pile of wrappers directly under the paste holder 5. Such a block 21 is desirable where the wrappers contain a 10 cord which thickens a portion of the same and causes an uneven pile.

To prevent the block 21 dulling the pins 18 when the latter move through the pile of wrappers, the block 21 is provided with recesses 22 to accommodate said pins.

In Fig. 5, I illustrate a modified shape of paste holder 23. In this form of my invention the paste holder is angular and I would have it understood that I may make the 20 paste holder of various shapes in accordance with the work to be done, but would embody in the paste holder of any shape, the features of construction above described.

While I have illustrated the sliding plate 25 13 as of flat metal rubbing against flat metal surfaces, it may be found desirable in some instances to utilize some sort of packing to prevent leakage.

In operation the wrappers are drawn 30 from under the paste holder and receive the desired amount of paste in accordance with the position of the plate 13 and the angular disposition of the paste holder. The paste holder feeds downwardly by gravity, the 35 rollers 4 facilitating such movement and insuring a proper feed at all times.

When it is desired to elevate the paste holder to insert a new pile of wrappers under the same, it is advisable to have some 40 supporting means for the paste holder. With this in view, I provide arms 24 which are pivotally secured to the standards 2 as shown at 25, and are adapted to swing to a horizontal position under the paste holder. 45 and rest upon lugs 26 on the standards. These lugs 26 limit the pivotal movement of the arms in one direction and permit the latter to support the paste holder while a new pile of wrappers are located in position.

When the wrappers are in position the paste holder is elevated slightly and the arms swung to the position shown in full line of Fig. 2 so that the paste holder is 55 free to move downwardly on to the wrappers.

Various slight changes may be made in the general form and arrangement of parts described without departing from my invention and hence I do not limit myself to the precise details set forth, but consider myself at liberty to make such changes and alterations as fairly fall within the spirit and scope of the appended claims.

65 Having fully described my invention,

what I claim as new and desire to secure by Letters Patent is:

1. A paste holder, comprising a receptacle having a pair of perforated bottoms spaced apart, and a sliding plate between 70 said bottoms adapted to cut off the perforations in both bottoms.

2. A paste holder, comprising a receptacle having a perforated bottom, a sliding plate supported on the perforated bottom, 75 and a removable perforated false bottom located inside the receptacle on top of the sliding plate.

3. A paste holder, comprising a receptacle having a perforated bottom, a sliding 80 plate supported on the perforated bottom, and a removable perforated false bottom located inside the receptacle and on top of the sliding plate, and upwardly projecting tongues on the false bottom having bent 85 upper ends.

4. A device of the character described comprising a base plate, a pair of standards on the base plate, a paste holder, brackets on the ends of the paste holder, means permitting said paste holder a movement angularly relative to the brackets, and means on the brackets having vertical movement 90 on the standards.

5. A device of the character described, 95 comprising a pair of standards, brackets movable vertically on the standards, a paste holder supported by the brackets, and means permitting said paste holder an angular adjustment relative to the brackets.

6. A device of the character described, comprising a base plate, a pair of grooved standards on the base plate, a paste holder, brackets on the ends of the paste holder, each bracket having a pair of vertically 105 aligned rollers thereon, movable in the grooves of the standards, said brackets having slots therein, and securing devices projected through the slots and into the paste holder, whereby the paste holder may be 110 tilted relative to the brackets.

7. A device of the character described, comprising a base plate, standards on the base plate, a paste holder, devices on the ends of the paste holder sliding in the standards and devices on the standards adapted to support the paste holder in an elevated position.

8. A device of the character described, comprising a base plate, standards on the 120 base plate, a paste holder, devices on the ends of the paste holder sliding in the standards, pivoted arms on the standards adapted to be projected under the paste holder and support the latter in an elevated position, 125 and lugs on the standards limiting the pivotal movement of the arms.

9. A device of the character described, comprising a base plate, a pair of standards on the base plate, a paste holder guided in 130

its vertical movement between the standards, a block supported on the base plate and adapted to support wrappers under the paste holder, pins on the paste holder puncturing the upper wrappers, and said block having recesses therein to receive the pins.

5 In testimony whereof I have signed my

name to this specification in the presence of two subscribing witnesses.

JOSEPH J. SLEEPER.
